CLIMBING DEVICE FOR POLES AND THE LIKE
Richard Carlo Merz, 30 Burgstockstrasse, and Karl Jans,
13 Molitorstrasse, both of Bad Waldsee, Wurttemberg,
Germany

Filed June 10, 1965, Ser. No. 469,027
9 Claims. (Cl. 182—92)

This invention relates to a climbing device for poles, masts, smokestacks, and the like, and more particularly to a ladder section or ladder component of such a climbing device. The present application is a continuation-in-part of application Serial No. 163,424, filed January 2, 1962, now abandoned.

There is a frequent need for climbing, for instance, electric light, telephone and telegraph poles for installing and repairing lines thereon. Such work, in addition to calling for a person to ascend and descend, often requires cables to be temporarily suspended, and various objects to be temporarily held in readiness, on the poles.

Climbing devices of the referred type are known. They are used in form of sectional ladders. The sections are applied individually to a pole and at a suitable distance one above the other. The known devices have the disadvantage that their sections cannot be locked securely to the pole or post and that there is often the danger that an individual section may tilt, which could endanger a worker standing on the respective section or lead to an undesired spilling of objects held in the section.

The primary object of our invention is to generally improve sectional ladders, and especially to simplify their construction and to render them more economical and safer.

One object of the present invention is to provide a component of a sectional ladder, which has a step part that will be braced against the pole in a horizontal position below the ordinarily used component-supporting strap means so that a person standing on the component, or any load on the component, will not merely be supported by the strap but also, to a considerable extent, by the pole itself.

Another object of the invention is to provide a ladder component the step part of which is braced against the pole at more than a single point so that horizontal turning of the step part is precluded.

Still other objects of the invention center about a sectional ladder which is reliable in every respect, and each component of which is made of an integral whole and includes, according to one aspect of the invention, guide means for wires or the like.

Further objects will be apparent from the following portion of this specification.

Broadly, the invention provides a component of a sectional ladder or climbing device for poles and the like, which comprises elongated pliable strap means that is to be laid around a pole and the like. The strap means includes resilient means and has two ends. The ladder component of the invention comprises further a mechanism to tighten the strap means and to lock same in the tightened condition, and rung means. The tightening and locking mechanism includes a lever member, arm means connected to one of the ends of the strap means, and an arresting member connected either directly or indirectly to the other of the strap means ends. The arresting member has the lever member pivotally connected thereto and permits the lever member to be swung from a strap means tightening and locking position into a strap means unlocking and releasing position and vice versa. The former of these two positions is the operative position in which the ladder component may actively be used, and the latter of the two positions is the inoperative position. The arresting member is provided with fixing means for releasably holding the

2

arm means in the operative position of the tightening and locking mechanism.

The specification is accompanied by drawings in which:

FIG. 1 is a fragmentary plan view of a ladder component, embodying features of our invention, of a climbing device, a pole to which the ladder component is applied being fragmentarily shown in section;

FIG. 2 is a front elevation of the ladder component of FIG. 1, there being only a difference in the lengths of the strap means shown;

FIG. 3 is a fragmentary plan view of a modified form of a ladder component of the invention, showing the tightening and locking mechanism of the component in unlocked condition;

FIG. 4 shows the same modification as FIG. 3 in locked condition; and

FIGS. 5 and 6 are a side elevation and front elevation, respectively, of the component of FIGS. 3 and 4.

Referring to the drawings in greater detail now, and initially to FIGS. 1 and 2, the ladder component shown is one of any number that may be used to climb up and down a pole and the like. Each component includes an elongated pliable strap that is laid around a pole 2 to support what will be referred to as a tightening and locking mechanism and as rung means. The tightening and locking mechanism will be called briefly "locking mechanism." The strap consists of a chain 1 and a tension spring 5. The latter terminates in two hooks and is fastened to one end of the chain 1 by a hook 3.

The locking mechanism includes a lever 6, an arm 9, and an arresting member 17. The arm 9 is shown as a closed loop which is fastened to the spring 5 by a hook 3a and passes through a hole 30 in the lever 6. The lever 6 and arm 9 are, thus, pivotally connected to each other at 30. The lever 6 is pivotally connected to the arresting member or arresting plate 17 at 16, and the arresting plate 17 is at one of its ends as at 31 fastened to the other end of the chain 1 and is provided with a notch 18 in its peripheral edge.

The rung means which is generally designated 32 consists of a step part 8, a mounting part including two rods 12 and a bracing part also including two rods, the latter being designated 13. These parts together form a basket-like structure. The step part 8 is formed by a crosswise extending rod 8a and two rods 8b extending from the crossrod 8a toward the pole. The mounting rods 12 extend from the inner ends of the rods 8b upwardly, and the bracing rods 13 converge from the ends of the crossrod 8a upwardly and in directions toward the pole. Each of the two bracing rods is shown in FIG. 1 to contact the upper end of one of the mounting rods 12. A plate 25 is another part of the rung means. Connected with the plate 25 for instance, by welding, are the plate 17 and end portions of the mounting rods 12 and bracing rods 13.

The function of the ladder unit or component of FIGS. 1 and 2 is as follows:

The chain 1 is laid around the pole 2 with the coiled spring 5 as a part thereof. The locking means and rung means are connected with each other, as has been indicated, by means of the plates 25 and 17, the latter being a part of the locking means, and the chain at one end thereof is permanently connected to the plate 17 at 31 while the spring 5 is releasably connected either to the chain at 3 or to the arm 9 at 3a. The spring 5 may also be releasable both at 3 and 3a. If the chain is laid around the pole while the spring 5 suspends immediately from an end of the chain, the arm 9 together with the lever 6 and the rung means suspend normally from the other chain end. If the chain is being mounted around the pole, and the spring 5 does not hang immediately from a chain end, then the spring, arm 9, lever 6, and rung means are all suspended from one and the same end of the chain.

Depending on which end of the spring 5 is free when the ladder component has been laid around the pole, connection is made either at 3 or 3a. The lever 6 which in the open condition of the locking means is in a position similar to the lever position shown in FIG. 3 will now be swung into the position shown in FIG. 1, which is similar to the lever position in FIG. 4. The lever 6 is turned about the pivot 16 to a point at which a bight of the arm 9 engages the notch 18 in the arresting plate 17. The locking mechanism is an over-center type of lock so that the hand lever 6 when turned beyond its pivot causes the arm 9 to remain locked in the notch 18. An additional locking help is afforded by a head 15 of the pivot pin 16 (see FIG. 6) which can be bypassed when the lever 6 is forced into its locking position. When in its locking position, the lever 6 is helped by the head of the pivot pin 16, acting as an abutment, to stay in the locking position.

As the lever 16 is moved into its closing position, it tightens the strap around the pole. If a strap is used that is longer than necessary in a given case, any excess length of the chain may be dealt with as is shown in FIG. 2. The end link of the overlong chain may be hung on a bar 22.

The embodiment of FIGS. 3 to 6 differs from that of FIGS. 1 and 2 mainly by added bracket means. On the side of the rung means facing the pole 2, there are bracing brackets which consist of an upper part 19 (best seen in FIGS. 3 and 4) and a lower part 19a (FIGS. 5 and 6), these parts being U-shaped when viewed in plan. The bight of the upper part 19 is shown to lean against an arresting plate 17'. The two bracket parts 19, 19a are connected by welding to a step part 8', a mounting rod 12', and bracing rods 13', and to each other by uprights 23 near the pole 2 and by the mounting rod 12' remote from the pole 2. The plate 17' is connected to both the upper bracket part 19 and the mounting rod 12'.

Two tension springs 5' rather than a single spring 5 are substantially parallel to each other and are hooked at one end into an arm 9' which is yoke-shaped (see FIG. 6) and is provided with outwardly and oppositely bent end portions 10. Each of the springs 5' is connected to one of the end portions 10 by a hook 3a'. A plate 11 having fastened thereto the springs 5' carries a hook 3' to be hooked into a link on one of the ends of the chain 1.

The rung basket according to FIGS. 3 to 6 has again two lateral rods 13' which are welded to the rear of a vertical plate 25' and thus are braced against the bracket 9, 9a and indirectly also against two circumferentially spaced points of the pole 2. Any load on the rung basket appears distributed over a portion of the circumference of the pole, which prevents slipping or sliding on the pole.

The ladder component of FIGS. 3 to 6 is similarly applied to a pole, and functions similarly, as the component of FIGS. 1 and 2. The yoke-shaped arm 9' acts as the closed loop arm 9 does, and the two springs 5' act as the single spring 5. The brackets 19, 19a serve bracing purposes most effectively by being supported at two circumferentially spaced points of the pole, and have the advantage of freely holding a rope and the like in place. While a rope 24 as shown in FIGS. 3 and 4 is held in place and prevented from coiling around the pole or from becoming tangled in any other way, it can easily be pulled upwardly or lowered along a straight line.

It is believed that the construction and operation of our sectional ladder, and the many advantages thereof, will be fully understood from the foregoing detailed description. Some of the features and advantages of the invention are pointed out and reviewed hereinafter.

Our sectional ladder may advantageously be used for climbing any kind of round pole, such as wooden and concrete poles, masts, columns, smokestacks, etc. In

dividual ladder components may be also used to support temporarily tools and other objects which are required while a particular work is carried out on the pole.

5 The step part of the rung basket as shown is braced against the pole within a horizontal plane below the strap tightened around a pole and the like so that the weight of a person standing on the basket, or any other load placed upon the basket, will not be merely supported by the strap but also, to a considerable extent, by the pole. The invention provides further that the bracing means of the rung basket engage the pole at at least two circumferentially spaced points within a horizontal plane (see FIGS. 1, 3, and 4). Any load applied upon a unit of the sectional ladder acts in the closing direction of the locking mechanism and thus increases the locking action and acts toward preventing an accidental unlocking.

In order to relieve the strap of a ladder unit as much as possible of its load, we provide that the distance, for instance, between the crossrod 8a of the step part of FIGS. 1 and 2 and the strap be greater than the distance between the center of the crossrod 8a and the points at which the crossrod and the bracing rods 13 meet.

Generally, it is preferable, although not essential, to provide a pair of springs rather than a single spring. FIGS. 5 and 6 show two parallel springs 5' to be connected to a common connecting plate 10. If two springs 30 are used, it is also possible to interpose a spring between each chain end and the locking mechanism. Two springs next to each other increase the safety of the attachment of the ladder component, while the use of a spring at each spring end facilitates the movement of the springs 35 during tightening of the strap involved.

Various materials may be used for the part of the strap, which is shown as a chain, for instance, a metal cable, a rope made of hemp or the like. It is generally advisable to give the strap a length which is substantially in accordance with the circumference of the kind 40 of pole to which the sectional ladder is usually to be applied. However, the strap may be made of greater length than necessary in a particular case so as to be usable in other cases as well. The free end portion 45 of the chain beyond the link into which the hook 3 is inserted (FIG. 2) may be strapped around the rung basket, and the end link of the free end portion hung on a short bar 22. In FIG. 6, an excess length of chain is designated 20 and provided with a hook 21 to be 50 conveniently hooked in a suitably located chain link. Excess length provides added safety inasmuch as the chain will even in the event of a breakage of the lock or the springs remain on the pole.

While in the embodiments of FIGS. 1, 2 and FIGS. 55 3 to 6 the chain is shown to be connected at one end to the arresting plate 17 and 17', respectively, the chain may as well be connected to the plate 25.

The chain of FIGS. 1 and 2 consists of parallel-sided links, and the chain of FIGS. 3 to 6 is made of twisted links. Twisted links have an advantage over parallel-sided smooth links since each link engages a pole in several points and thus exerts a better gripping action. When applied to an ice-coated pole, the contacting points of 60 twisted links bite much more frequently through the ice and into the surface of the pole. With parallel-sided links, only every other link engages the pole.

The head 15 of the pivot pin 16 affords an added action to that of the locking mechanism.

It will be apparent that while we have shown and 70 described our invention in a few forms only many changes and modifications may be made without departing from the spirit of the invention defined in the following claims.

We claim:

1. A component of a sectional ladder for poles and 75 the like, comprising

- (a) elongated pliable strap means to be laid around a pole and the like, including resilient means, said strap means having two ends,
- (b) a mechanism to tighten said strap means and to lock same in the tightened condition, said mechanism including
- (1) a lever member,
  - (2) arm means connected to one of said ends, and
  - (3) an arresting member connected at least indirectly to the other of said ends, said arresting member having said lever member pivotally connected thereto, said lever member being adapted to be swung from an operative or a strap means tightening and locking position into an inoperative or a strap means unlocking and releasing position, and vice versa, said arresting member having holding means for releasably holding said arm means in said operative position, and
- (c) rung means fixedly connected to said arresting member, said rung means having a step part, said step part, with the ladder component in operative condition, being disposed so as to be below said strap tightening mechanism.

2. In the ladder component according to claim 1, said arm means and said arresting member having complementary locking means including said holding means, and being arranged so that said arm means and said arresting member are interlocked when said lever member is in said operative position.

3. In the ladder component according to claim 2, said arresting member being formed as a plate having a peripheral edge and a notch in said edge, said arm means and said notch forming said complementary locking means.

4. In the ladder component according to claim 1, said resilient means being constituted by at least a single tension spring interposed between said arm means and the remainder of said strap means.

5. In the ladder component according to claim 1, said rung means including said step part, a mounting part, and a bracing part, said step part including at least a crosswise extending member, said mounting part including at least a single vertically extending member, said bracing part including two members extending from the ends of said crosswise extending member upwardly and toward the pole said component is to be applied to.

6. In the ladder component according to claim 5, the two bracing members bearing against two circumferentially spaced points on said pole.

7. In the ladder component according to claim 5, bracket means including an upper part interposed between said pole and said tightening and locking means, and a lower part interposed between said pole and said crosswise extending member, each of said upper and lower parts bearing against two circumferentially spaced points on said pole.

8. In the ladder component according to claim 5, said step part being braced against said pole within a horizontal plane below said strap means when tightened around said pole.

9. In the ladder component according to claim 5, the distance between said crosswise extending member and said strap means when tightened around said pole being greater than the distance between the center of said crosswise extending member and any one of the points at which said crosswise extending member and one of the two bracing members meet.
